METHOD OF MAKING AN ARTIST'S MAT

Arthur B. Glenn, Los Angeles, Calif.

Original application December 7, 1927, Serial No. 238,410. Divided and this application April 2, 1930. Serial No. 441,036

3 Claims. (Cl. 101—401.1)

This invention relates generally to printing and more particularly to stereotyping.

According to methods now generally in use, in preparing a stereotype, it is necessary for the 5 artist to prepare a drawing on paper. Usually a photograph must be made from this drawing, and an engraving or a matrix is formed thereafter from which the print or stereotype is produced.

10 It has been attempted heretofore to prepare a matrix for stereotyping by having the artist draw directly upon a metal plate having a facing consisting of a layer of chalk. According to this method, the artist etched the facing with a sharp 15 stylus, thereby producing a matrix which could be used in producing a stereotype.

In etching upon this mat the point of the stylus of course, in forming a line, penetrated through the entire depth of the facing, down to the 20 backing sheet of metal. When in the mold the type metal flowed into these engraved lines and the face of the metal plate backing sheet determined the position of the printing faces of the stereotype corresponding to the engraved lines.

25 This method has been found unsatisfactory for the reason that the metal plate is a conductor of heat and chills the molten metal rapidly, leaving an inefficient and chilled face on the stereotype, and also because the chalk and compositions heretofore used to form the facing of the 30 mat have been found to be brittle. Due to the fact that a metal plate makes a poor backing sheet, chilling rapidly, and to the brittleness of the chalk, it is impossible for the artist to produce a clean, unbroken line. Heretofore no material has been discovered suitable for making 35 the facing of such a mat. Such a facing must be soft enough to permit the artist to draw upon it readily without cracking off on the edges of the lines formed by the stylus, and furthermore, the facing must be sufficiently elastic to prevent it from forming cracks when handled, shipped, or when kept in stock for indefinite periods. The 40 material forming the facing must also resist the temperature and weight of the type metal when flowed over it in the mold.

The general object of this invention is to provide a method which will enable the artist to 45 produce a matrix directly, thereby eliminating steps now necessary in the usual methods of producing stereotypes. One of the objects of the invention is to produce an efficient method to be used in forming a mat upon which the artist may draw or etch directly to produce a matrix 50 and enabling the mat to have characteristics

which will enable it to be used directly in a stereotype mold.

One of the objects of the invention is to provide a method which will avoid the use of metal in producing the mat.

It is sometimes desired to send engravings to distant points through the mail or by express. The matrix prepared according to my invention can be readily sent through the mails without danger of injury and it is one of the objects 65 of the invention to produce a method which will meet this requirement. Further objects of the invention will appear hereinafter.

The present application is a division of my former application, Serial No. 238,410, filed December 7, 1927.

The invention consists in the novel steps and combination of steps in the method to be described hereinafter, which steps cooperate to produce an efficient method for forming a mat 75 suitable for forming a matrix.

A preferred embodiment of the invention is described in the following specification, and the broad scope of the invention is pointed out in the appended claims.

In the drawing:

Figure 1 is a side elevation illustrating the first step in the production of the mat.

Figure 2 is a side elevation illustrating the mat at a further stage in its manufacture; this view 85 particularly illustrates the finishing of the mat to the desired thickness.

Figure 3 is a cross-section through the completed mat.

Figure 4 is a vertical section through a molding box and illustrating the manner in which the matrix is employed in forming the stereotype; and

Figure 5 is an illustration showing, as an example, a character of print that can be produced 95 from a stereotype manufactured in accordance with my invention.

Before proceeding to a detailed description of this invention, it should be stated that the present application is a division of my pending application Serial No. 238,410 filed December 7, 1927.

In practicing the invention, I prefer to employ a backing sheet which is in the form of a dense, 105 pressed paper board. A suitable board for this purpose is sold in the market under the name of Vehisote or Masonite, or pressed wood board. The backing sheet must have certain properties which are important as affecting the character 110 of the printing face of the stereotype. In this

connection, it should be understood that in drawing upon the mat the artist scratches or etches completely through the facing on a backing sheet, and for this purpose uses a sharp stylus of steel, or similar material. The face of the backing sheet should be such that the point of the stylus will not raise any fibres from the face of the backing sheet or scratch the face of the backing sheet. In other words, the face of the backing sheet which carries the facing of my composition should be hard and resistant to the action of the stylus. I do not use a metal backing sheet for the reason that casting metal directly against metal has a tendency to chill the stereotyping metal and mars the printing face of the stereotype formed; also such a backing sheet tends to expand from the heat in the mold and produces buckling or bulges in the matrix which interfere with the production of perfect stereotypes. I have found that the paper backing sheet described effectively carries the facing and at the same time resists the temperature of the type metal when flowed onto it in the mold, maintaining the heat of the metal and producing perfect reproductions.

In the drawing, 1 indicates a backing sheet of paper board of the character suggested above. In preparing this backing sheet, I prefer to dress it down to a thickness of about $\frac{1}{16}$ " after which I coat the faces of the sheet with shellac, using, however, just sufficient shellac to be absorbed by the surface of the board. This produces a smooth face on the board and admirably adapts it to produce a clean printing face for the stereotype. The composition which I prefer to use to form the facing for the mat is a mineral earth and preferably is composed substantially or principally of magnesium-silicate. For this purpose, I prefer to employ purified talcum powder. In preparing the composition, I mix together certain ingredients, including substantially one part of ground glue by measure to eight parts of water by measure. To this I add about two ounces of yellow Diamond Dye for each gallon of the glue and water. The Diamond Dye is included as a coloring and to give a smoother texture to the composition. In order to increase the preserving qualities, I prefer to add a few drops of crude carbolic acid. I mix the above ingredients with a quantity of the base or purified talcum powder in such quantities as to form a batter-like mixture of approximately the consistency of soft mud or heavy pancake batter. In other words, I form a thin mush or thick paste from these ingredients.

On the upper face of the backing sheet 1, I heap a mass 2 of this paste (see Figure 1). This should be done to a considerable depth, preferably about $\frac{1}{3}$ " for a reason which will appear hereinafter. While the paste is still moist, I wipe off the edge portions 3 to a point indicated by the dotted lines in Figure 1. This leaves a margin on the backing sheet uncovered by the paste.

I find that in applying the paste to the backing sheet, it is necessary to take steps to insure that the composition in the vicinity of the face of the backing sheet will be dense, that is to say, that the particles of the composition at this point will be tightly packed together. This is necessary in order to insure a continuous and unpitted face in the finished mat. For this reason, I prefer to jog the unfinished mat while the moist paste is resting upon it. This jogging settles the mass

2 and insures the desired density in the lower strata of the composition.

The backing sheet with the paste 2 upon it is then dried in an oven. The temperature in the oven should not exceed about 250° F., and should not be sufficient to bake the paste. The function of the oven is merely to dry the paste and no boiling or baking of the paste should take place. The drying should be effected quickly. However, it is not essential that the drying be effected in an oven, and if desired, the mass can be dried in the air or in the sun providing the temperature is not permitted to rise too high.

When the paste has become thoroughly dry, it will be found that a portion of the liquid in the composition has risen to the upper layers of the paste, forming a thin, hard coating, but this liquid which operates as a binder operates effectively to cause the dried paste to adhere firmly to the face of the board; below this thin, hard coating the composition will be found to be soft and pliable, yet with its particles firmly bound together.

It is then necessary to remove the upper portion of the dried mass. This is accomplished by running the mat through a sander or preferably through a planer having a planer tool 4 with a plurality of knives 5 such as illustrated in Figure 2. In this operation, I prefer to dress the hardened paste 6 so as to leave a facing 7 on the backing board of approximately $\frac{1}{16}$ " in thickness. This thickness, however, may be varied as desired to suit the special requirements of the trade. The planer or sander leaves a smooth, uninterrupted face 8. If the mat is prepared as described above, this face will be found to be devoid of pits or inequalities in its face.

The finished mat illustrated in Figure 3 is then ready to be drawn upon or etched by the artist who uses for this purpose a stylus, hard pencil or other sharp instrument.

In making the drawing, however, the artist should take care that the point of the stylus in making any line of the drawing penetrates completely through the layer 7 and comes in contact with the upper face of the backing sheet. This is necessary to insure that all the printing faces of the completed stereotype will be "type high".

In this way a matrix 9 is formed such as illustrated in Figure 4 which can be placed in a casting box 10 with the engraved facing 7 of the matrix uppermost. The mold having been closed and clamped up, its interior may be filled with a type metal composition to produce a stereotype 11. In this view the engraved lines 12 indicate how the engraving is brought down to the face of the backing sheet so as to insure a stereotype that will print perfectly. While the mat is particularly adapted for making line drawings, it is evident that by scraping away small areas of the facing of the matrix, solid black areas in the print can be produced. A good example of the character of a print that can be formed by this method is illustrated in Figure 5.

The glue in my composition of course operates as a binder and also causes the composition to adhere to the backing sheet.

The relatively great depth of the paste assists in increasing the density of the composition at the level of the face 8.

The mat produced in accordance with my method need not be handled with great care, that is to say, the facing 7 is relatively tough and resili-ent, and in fact the mat can be bent considerably

without injury to the facing. The facing has sufficient resiliency to permit this.

While the matrix described herein may be used for producing stereotypes, it also may be used in 5 the bottom of a small mold for molding rubber to produce a rubber stamp.

One of the principal advantages of the use of my invention arises from the fact that I avoid the use of a metallic backing sheet and employ a backing sheet of a material having no chilling effect 10 upon the type material when it is run into the mold. This enables fine and accurate reproductions to be produced from the matrix.

What I claim is:

- 15 1. The method which consists in laying a paste of mineral earth on the upper face of a flat backing sheet of paper board, drying the paste thereafter, jogging the backing sheet to condense the paste, removing the upper portion of the dried 20 paste to form a substantially flat face and leave a relatively thin layer of relatively dense material on the backing sheet, etching the face of the backing sheet to form a matrix, and forming a stereotype in type metal directly from the matrix.

2. The method of making an artist's mat to form a matrix for a stereotype which consists in forming a paste of finely divided magnesium-silicate, laying the said paste on the upper face of a flat backing sheet, jogging the backing sheet and paste thereafter to increase the density in the particles of the paste nearest to the face of the backing sheet, drying the paste thereafter and then removing the upper portion of the dry paste to form a substantially flat face on a relatively thin layer of the material.

3. The method of making an artist's mat to form a matrix for a stereotype which consists in varnishing the upper face of a flat backing sheet of fibrous material, forming a paste of finely divided magnesium silicate, laying the said paste on the upper varnished face of the backing sheet, drying the paste thereafter, and then removing the upper portion of the dried paste to form a substantially flat face on a relatively thin layer of the material.
